Original application December 16, 1938, Serial No.
246,235. Divided and this application Septem-
ber 1, 1939, Serial No. 293,111

6 Claims. (Cl. 22—82)

This invention relates to a crucible support, and more particularly to a portable crucible tongs mechanism, and is a division of my copending application Serial No. 246,235, filed December 16, 5 1938.

In my copending application I have disclosed a crucible support having a supporting structure adapted to extend transversely over the top of a crucible furnace and having depending tongs engageable with the crucible to lift it from the furnace whereby the metal may be poured therefrom. The tongs device forms the subject matter of my copending application and comprises a pair of tong arms at least one of which is movably 10 connected to the transverse supporting member and has novel means associated therewith for clamping it into engagement with a crucible in the furnace. The mechanism is intended to be used in connection with relatively small crucibles 15 which are capable of being manually removed from the furnace.

An important object of the present mechanism is to provide a handle structure for a crucible tong mechanism which facilitates the handling of the 20 device in gripping a crucible, removing it from the furnace and pouring the metal therefrom.

A further object is to provide a device of this character wherein the handle structure is so related to the other elements of the mechanism as 25 to render it extremely easy to manually tilt the crucible to pour metal therefrom.

A further object is to provide a pair of handles at opposite ends of the device, connected to the support which extends across the furnace, 30 and depending substantially below the support 35 so that the manual lifting force is applied slightly above the center of gravity of the supporting device and the crucible whereby the crucible may be readily removed from the furnace and carried 40 to the pouring point without any tendency to tilt, and wherein the arrangement of the handles with respect to the center of gravity permits the tilting of the crucible with minimum effort.

A further object is to provide a device of the 45 character referred to wherein the handles of each pair are spread apart a substantial distance to afford leverage in the tilting of the crucible to facilitate the pouring operation with little manual effort.

Other objects and advantages of the invention 50 will become apparent during the course of the following description.

In the drawing I have shown one embodiment of the invention. In this showing:

Figure 1 is a side elevation showing the mech-

anism in operative engagement with a crucible located in a furnace.

Figure 2 is a plain view of the mechanism shown in Figure 1.

Figure 3 is a sectional view taken on line 3—3 of Figure 1.

Figure 4 is a sectional view taken on line 4—4 of Figure 1, and

Figure 5 is a perspective view of a part of the mechanism.

Referring to Figure 1, the numeral 10 indicates a furnace having a crucible 11 supported therein on a pedestal 12. The numeral 13 indicates the mechanism as a whole by which the crucible 11 may be manually transported, the mechanism 13 being shown in operative position for the removal 15 of the crucible 11 from the furnace.

The mechanism 13 comprises a supporting structure 14 having spaced parallel bars 15 and 16, rigidly fastened to transverse plates 17 and 18 located at opposite ends thereof. The plates 17 and 18 depend a substantial distance below the bars 15 and 16 and each is provided with a pair of handles 19 secured adjacent the lower edge thereof.

Gripping members 20 and 21 are provided and have gripping surfaces which are engageable with the surface of the crucible 11 for supporting the same. A pair of brackets 22 and 23 are respectively secured to the bars 15 and 16 and cooperate 30 therewith to support the gripping member 20. Likewise, a pair of brackets 24 and 25 are rigidly secured to the members 15 and 16 respectively and these brackets support the gripping member 21.

The gripping member 20 is rigidly secured to the supporting structure 14 by two fastening members 26 and 27 as best shown in Figure 3. The gripping member 21 is pivotally supported with respect to the supporting structure 14 by 40 a pivot pin 28 extending through the lower ends of the brackets 24 and 25 as shown in Figure 4. A resilient bar 29 is secured at one end to the upper end 30 of the member 21 and is used as a lever arm for forcibly moving the member 21 45 about its pivot 28 toward the gripping member 20 to securely clamp the gripping members against a crucible arranged therebetween.

Plates 31 and 32 are secured to and project 50 upwardly above the bars 15 and 16 respectively and are located in such a position that the bar 29 will occupy a position between the plates 31 and 32 when the gripping members 20 and 21 are in engagement with a crucible. The plate 32 has a plurality of openings 33 formed therein which 55

are respectively in alignment with similar openings 34 formed in the plate 31. With the gripping members 20 and 21 in clamping engagement with the crucible 11 and the member 29 positioned between the plates 31 and 32, a pin 35 may be passed through aligned openings 33 and 34 in the plates 32 and 31, respectively, above the bar 29 to lock the latter in operative position. The bar 29, being resilient, will be sprung downwardly by the application of force after initial engagement of the gripping member 21 with the crucible 11 and it will be obvious that the resilience of the member 29, tending to restore it to the position shown in dotted lines in Figure 1, will be prevented from swinging upwardly by the locking pin 35 thereby holding the member 21 in tight engagement with the crucible 11.

The gripping surfaces of the members 20 and 21 are shaped to conform to the crucible to be engaged and supported thereby and different sizes may be provided for different sized crucibles. In order that the gripping surfaces of the members 20 and 21 will be properly positioned with respect to the sides of the crucible, it is desirable to provide adjustable means for positioning the gripping members 20 and 21 with respect to the crucible. This is accomplished by an adjustable plate member 36 which is engageable with the top of the crucible 11. The plate 36 is provided with upright members 38 and 39 carried thereby which are slidable in guides 40 and 41 secured by suitable fastening devices to the bars 15 and 16. Set screws 42 and 43 are provided for adjustably positioning the members 38 and 39 in the guides 40 and 41 in order that the plate 36 will be properly positioned with respect to the gripping members 20 and 21. A similar arrangement for positioning the gripping members with respect to the top of the crucible is shown in my copending application filed September 27, 1938, Serial No. 232,005.

The operation of the apparatus is as follows:

The members 38 and 39 are adjusted to place the plate 36 at a proper position relative to the gripping members 20 and 21 in order that the gripping members will be placed at a proper position with respect to the side of the crucible to engage thereagainst. The mechanism 13 is then lowered until the plate 36 contacts the upper edge of the crucible 11. The mechanism 13 is placed in a position with the immovable gripping member 20 in engagement with one side of the crucible 11, whereupon the movable gripping member 21 is moved about its pivot 23 toward and into engagement with the other side of the crucible. A downward pressure is applied to the free end of the resilient member 29 to force the gripping member 21 into tight engagement with the side of the crucible. Such downward pressure will cause a deformation of the resilient member 29 from the dotted line position to the solid line position in Figure 1. The locking pin 35 is then inserted through a pair of aligned openings 33 and 34, in the members 32 and 31, respectively, immediately above the resilient member or lever 29. The locking pin 35 will retain the member 29 in its deformed position and the crucible 11 will thereby be securely clamped between the crucible gripping members 20 and 21.

70. The crucible 11 may then be removed from the furnace by operators who will grasp the handles 19 and lift the mechanism 13 and thereby remove the crucible 11 from the furnace.

A decided advantage is secured by having the handles 19 located as shown in Figure 1. By hav-

ing the handles located in a common plane substantially lower than the supporting frame 14, such plane may be located just above the center of gravity of the combined mechanism 13 and crucible 11. This arrangement will enable the operators to tilt the crucible supported by the mechanism 13 to pour molten metal therefrom with a minimum of effort. In order to tilt the crucible to pour metal therefrom, it will only be necessary for the operators to apply slightly more force to the handles located at one side of the parallel members 15 and 16 than is applied to the handles 19 located at the other side thereof.

Particular attention is invited to the fact that the handles 19 of each pair are arranged a substantial distance apart and the horizontal plane of the handles is preferably slightly above the center of gravity of the crucible and its contents, and the supporting mechanism as a whole. This relative arrangement of the handles is important for two reasons. The center of gravity of the assembly being slightly below the handles 19, two operators can lift the crucible from the furnace and transport it to the pouring point without any tendency of the crucible to tilt and spill metal therefrom. The arrangement of the handles near the horizontal plane of the center of gravity and the spacing of the handles of each pair a substantial distance from each other provides the two operators with adequate leverage whereby the movement of the handles necessary to tilt the crucible to pour metal therefrom may be accomplished with little manual effort.

When it is desired to release the crucible from the mechanism, it merely is necessary for an operator to exert a downward force on the free end of the bar 29 to relieve the pressure thereof from the pin 35. This pin then may be easily withdrawn, whereupon the bar 29 is free to move upwardly to release the gripping member 21 from the crucible. Thus the mechanism will be free to be moved upwardly wholly out of engagement with the crucible.

From the foregoing, it will be apparent that I have provided a simple and inexpensive apparatus for removing a crucible containing molten metal from a furnace. In addition to providing mechanism which greatly simplifies the removal of a crucible from a furnace, I have also provided mechanism which will enable the metal to be poured from the crucible with a minimum of effort.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. In a mechanism for engaging and supporting a crucible, a horizontal supporting structure formed of a pair of spaced parallel members, a pair of crucible gripping devices carried by said structure and depending therefrom, said devices having their upper end portions arranged between said parallel members, plates connecting said parallel members at each end of said supporting structure, and a pair of handles carried by each plate and projecting outwardly therefrom, said handles being arranged in a common horizontal plane slightly above the center of gravity of said supporting structure, said crucible engaging devices and the crucible.
2. In a mechanism for engaging and support-

- ing a crucible, a supporting structure elongated horizontally and adapted to extend over the top of a furnace and a crucible therein, a pair of crucible gripping members engageable against 5 the sides of a crucible intermediate the top and bottom thereof and at diametrically opposite points, said members being connected to said supporting structure and depending therefrom, and being constructed and arranged to extend 10 downwardly into the furnace on opposite sides of the crucible therein, means operable from above the furnace for moving said crucible gripping members into clamping engagement with said crucible, and means located substantially below 15 the level of said supporting structure furnishing a manual grip for lifting said mechanism and the crucible supported thereby.
3. In a mechanism for engaging and supporting a crucible, a supporting structure elongated 20 horizontally and adapted to extend over the top of a furnace and a crucible therein, a pair of crucible gripping members engageable against the sides of a crucible intermediate the top and bottom thereof and at diametrically opposite points, 25 said members being connected to said supporting structure and depending therefrom, and being constructed and arranged to extend downwardly into the furnace on opposite sides of the crucible therein, means operable from above the furnace 30 for moving said crucible gripping members into clamping engagement with said crucible, and handles connected to said supporting structure on opposite sides of and horizontally spaced from said gripping members furnishing manual grips 35 for lifting said mechanism and the crucible supported thereby, said handles being located in a horizontal plane passing adjacent the center of gravity of said mechanism and the crucible supported thereby.
- 40 4. In a mechanism for engaging and supporting a crucible, an elongated horizontal supporting structure having a pair of crucible gripping devices equidistantly spaced on opposite sides of the center of the length thereof and depending

therefrom for gripping engagement with opposite sides of a crucible intermediate the top and bottom thereof, and means for transporting said structure comprising handle devices fixed with respect to the ends of said supporting structure 5 and arranged approximately in the horizontal plane of the center of gravity of said supporting structure and the crucible supported thereby.

5. In a mechanism for engaging and supporting a crucible, a horizontally elongated supporting structure, a pair of crucible gripping devices at least one of which is pivotally connected to said supporting structure, said gripping devices depending from said supporting structure and having gripping elements at their lower ends engageable against opposite sides of a crucible intermediate the top and bottom thereof, means for effecting relative gripping engagement of said elements against the crucible, and means for transporting said structure comprising handle 10 devices arranged slightly above the center of gravity of the mechanism and the crucible supported thereby, and means rigidly fixing said handles with respect to the ends of said supporting structure, said last named means being 15 spaced apart a distance greater than the diameter of the furnace which receives said crucible.

6. In a mechanism for engaging and supporting a crucible, a horizontal supporting structure formed of a pair of spaced parallel members, a pair of crucible gripping devices carried by said structure and depending therefrom, said devices having their upper end portions arranged between said parallel members, rigid means connecting said parallel members at each end of 30 said supporting structure and depending therefrom, and handle means carried by the depending portions of said rigid means at opposite ends of said supporting structure and projecting outwardly from said rigid means, said handle means 35 being arranged in a common horizontal plane slightly above the center of gravity of the mechanism and of the crucible supported thereby.

RAYMOND D. YORK.
